JACQUES GUSTAVE SCHULZ, OF PARIS, FRANCE.

DRIVING-WHEEL FOR MACHINES MOVING OVER SOFT GROUND.

1,386,281.

Specification of Letters Patent. Patented Aug. 2, 1921.

Application filed July 30, 1920. Serial No. 400,176.

To all whom it may concern:

Be it known that I, JACQUES GUSTAVE SCHULZ, citizen of the Republic of France, residing at Paris, France, have invented certain new and useful Improvements in Driving-Wheels for Machines Moving Over Soft Ground, of which the following is a specification.

The mechanical propulsion of machines, known at the present time, over arable soils or other soft ground is obtained by means of driving wheels furnished on the periphery of the rim with spikes which penetrate into and grip the soil and thus prevent slipping, or by means of caterpillars, winches or tractors. The three last methods have been devised to remedy the following disadvantage of the driving wheels furnished with spikes, for with the latter as soon as the soil is a little greasy, a clot of earth forms between the projections totally or partially masking them, which prevents sufficient penetration of the spikes into the soil and the wheel slips.

The object of the present invention is to clean the hollow spaces between the spikes and thus allow the practical provision of a driving wheel provided with spikes on the periphery thereof free from the disadvantage above mentioned.

A construction embodying my invention is illustrated by way of example on the accompanying drawings, in which:

Figure 1 shows above the axle designated by the broken line $o-o$ a transverse vertical section of the contrivance, and beneath this axle an edge view of the driving wheel.

Fig. 2 is a side elevation of the contrivance and driving wheel.

Fig. 3 is an elevation of the wheel and its cleaner mounted on a vehicle.

A shaft designated in Fig. 1 by the broken line o^1-o^1 outside the driving wheel a and parallel to the axle o of this wheel, carries scrapers b .

These scrapers are intended to remove the soil which accumulates in the spaces between the spikes of the wheel a .

The holder mounted on the rotatable shaft o^1-o^1 has a plurality of arms, each arm carrying a number of scrapers, *e. g.* three. Each scraper consists of a steel-blade. The extremity of each steel blade is beveled; the edge thus formed is parallel to the shaft o^1 , and scrapes off the earth lodged in the spaces between the spikes of the wheel a .

The distance separating the two axes of

$o-o$ and o^1-o^1 is constant. Both are carried by the frame of the machine.

While the wheel a turns around its axle $o-o$, the tool-holder turns in the opposite direction with its shaft o^1 . These two motions are interdependent and the ratio of their speeds is determined by the requirement that at each revolution of the wheel a one scraper, and only one, passes into each of the spaces between the spikes of this wheel.

If therefore the latter, has an angular velocity ω , and N spikes and the shaft o^1-o^1 n scrapers, the angular velocity ω^1 of this shaft o^1 must be

$$\omega^1 = \frac{\omega N}{n}$$

Moreover the scrapers must pass into each of the spaces between the spikes of the wheel a and also be there displaced in such a manner that their edge, in passing as closely as possible to the sides of these spikes and the part of the rim separating them, will clear away the accumulated soil from these surfaces.

This result is obtained by employing with the set of scrapers previously described, spikes of such a shape that the profile of the hollow which unites their edges with each other may fulfil this condition.

This profile c will be obtained by a geometric construction analogous to that for the generation of spur-gearing, but in which the profile of the pinion tooth would be reduced to a point, which in this case, represents the edge of one of the scrapers.

In such geometric construction, the radii R and R^1 of the pitch circles are given by the two ratios:

$$\begin{aligned} R + R^1 &= oo^1 \\ \frac{R}{R^1} &= \frac{\omega^1}{\omega} = \frac{N}{n} \end{aligned}$$

Care must be taken in fixing oo^1 , N and n , to select them in such a way that, conversely to what happens with gearing where an endeavor is made to reduce friction to a minimum, the part utilized of the profile c will not be astride the pitch circle of the wheel, but, on the contrary, situated distinctly outside this circle, in order to obtain a continual gliding of the scraper on the surfaces of the hollow separating the spikes and thus obtain an effective scraping action.

The number of spikes of a wheel being previously fixed, their theoretical height is determined by the intersections d of the suc-

cessive profiles *c*, obtained as previously stated, the said intersections giving the theoretical situation of the edges of the spikes.

5 In the example given on the accompanying drawings of an embodiment of the invention, $n=2$ and $N=16$ have been selected.

10 The profile *c*, obtained as previously explained, gives the general form of the hollow 10 separating the edges of two consecutive spikes.

15 In practice it is replaced by the profile *e f g h*. Of this profile, *f g* is a portion of the wheel rim and *g h* are the opposing sides of two consecutive spikes. This profile *e f g h* should be entirely, somewhat outside the theoretical profile *c*, to allow the scrapers *b* to work in the spaces between the spikes of the wheel, without their edges, owing to 20 play of the mechanism, coming into contact with the sides. In fact it is not necessary to have friction between the edges and the sides to obtain a satisfactory removal of the soil. It is sufficient if the edge just clears 25 the sides.

30 The driving wheel and the tool holder, the movements of which must be interdependent are, in the example given, connected with one another by the following driving connection:—

35 An internal spur wheel *i* is secured to the driving wheel. It drives a toothed pinion *k*, carried by one extremity of an intermediate shaft *l*, the other end of which carries a spur wheel *m*, which in turn drives a spur pinion *n*. This latter is fast with the tool holder and is mounted on the shaft $\sigma^1-\sigma^1$.

40 In the first place, it is seen that by the preceding driving connection, the motions of the driving wheel and tool holder are inverse. Moreover considering that in the example given $n=2$ and $N=16$ the relation between ω and ω^1 must be

$$45 \quad \frac{\omega^1}{\omega} = \frac{16}{2} = 8$$

50 Thus for each of the two pairs of spur gearing previously described, the following ratios have been taken:—4 for the first pair (that which has an internal spur wheel) and 2 for the second. Thus $2 \times 4 = 8$ is obtained.

55 Moreover to facilitate machining of the rim of the driving wheel and enable at the same time, the interchangeability of the spikes and their construction in a metal harder than the remainder of the wheel, these spikes are not formed on the wheel itself, but are applied and connected to this 60 wheel by dove tail joints.

On the other hand to obtain a better grip of the wheel on the soil, each spike is not continuous nor equal in length to the thick-

ness of the driving wheel, but is formed by a row of teeth *p*, three in number. In the 65 example given on the accompanying drawings these teeth are interchangeable and placed between the two same generating lines of the driving wheel *a*; they are separated from each other by free spaces *q* the 70 dimensions of which are determined by practice.

In two consecutive rows of teeth, the teeth are arranged staggered in such a way that an empty space *q* is opposite a tooth *p* of the 75 succeeding row. This arrangement assures, in the machine which forms the subject of the present invention the advantage of offering less resistance to removal of the soil by the scrapers. Finally each scraper, instead 80 of being in one piece will, with advantage, be constituted by a series of scrapers placed side by side and corresponding each with a tooth.

85 The scraper *b* is grooved at *r* so as to form a section of reduced resistance, where rupture of the scraper will occur if too great a resistance is encountered, arising for example, from a stone lodged between a scraper 90 and a spike of the driving wheel.

90 It may be added that in the case of backward running when, owing to play of the gearing, the scrapers and spikes of the wheel come into contact, it will be sufficient to mount these scrapers on trippers working 95 only in the reversing direction and allowing the scrapers to give way to the spikes when they meet.

Claim.

100 The combination with a spiked driving wheel for machines intended to move over soft ground, of a rotary scraper-wheel adapted to rotate about an axis of fixed relative position in the frame of the machine, and scrapers carried by the said wheel 105 scraper so as to remove the soil between the projections of the said driving wheel, the outer profile of the said driving wheel being such that at each rotation of the same, the scraping edges of the scrapers carried by the 110 said scraper-wheel pass with a slight clearance over the entire surface of each projection, the rotation of the said scraper-wheel being in opposite direction to that of the said driving wheel so that upon the rotation of the said two wheels the scrapers carried by the said scraper-wheel successively enter the depressions between the projections of the said driving wheel.

115 In testimony whereof I have affixed my 120 signature in the presence of two witnesses.

JACQUES GUSTAVE SCHULZ.
